AUTOMOBILE MIRROR

Robert K. Stortz, Bellwood, Ill.

Application March 5, 1957, Serial No. 45,118

Term of patent 7 years

(Cl. D14—6)

FIG. 1

FIG. 2

FIG. 3

Fig. 1 is a side elevational view of an automobile mirror, showing my new design;

Fig. 2 is a top plan view; and

Fig. 3 is an end elevational view taken from the right of Fig. 1.

The essential features of my design reside in the portions shown in full lines.

I claim:

The ornamental design for an automobile mirror, substantially as shown and described.
